UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

LINE-CASTING MACHINE.

1,115,208.

Specification of Letters Patent. Patented Oct. 27, 1914.

Application filed May 6, 1911. Serial No. 625,616.

To all whom it may concern:

Be it known that I, DAVID S. KENNEDY, a citizen of the United States, and a resident of Brooklyn, county of Kings, and State of New York, have invented a new and useful Improvement in Line-Casting Machines, of which the following is a specification.

My invention relates to linotype machines, and more particularly to that class thereof wherein a plurality of independent magazines are employed, and wherein the distributing mechanism automatically distributes the matrices to the proper tubes or channels in the respective magazines. It is often found desirable to have conveniently at hand a considerable number of matrices representing additional characters, and it is to this end that I employ a plurality of magazines, the escapements of which are controlled by independent keyboards, and whereby they are delivered to a common belt, which in turn conveys them to the assembling point, and wherein a common distributing rail redelivers the matrices to their respective magazines. In these and many essential respects the general construction is similar to that shown and described in the patent to Muehleisen, No. 608,067, granted July 26th, 1898.

Although only two magazines are herein illustrated, it will be obvious that the common assembling and distributing mechanisms may be extended to include any number of additional ones.

It is a prominent feature of my invention to construct the machine so that one or more of these magazines may be removed and replaced by others, such removal and replacement not necessarily affecting the relation of the substituted magazine to its keyboard and the common assembling devices, although if it contain a different number of receptacles or channels, or if the receptacles or channels are intended to contain matrices of greater or less thickness, it becomes necessary to alter the distributing mechanism.

In the Muehleisen patent previously referred to, the magazines are arranged side by side and an integral distributing bar or rail is provided which extends entirely across the mouths of the channels in both magazines. If such construction were closely followed in the present case, it would be necessary to change the entire distributor bar,

when a magazine is substituted containing matrices of greater or less thickness. As it is my purpose to permit the employment of a considerable variety of such interchangeable magazines, it would then be necessary to have a correspondingly large variety of distributor bars or rails, formed with different combinations and permutations of the distributing grooves. This would involve great expense and inconvenience, and it is a principal feature of my present invention to dispense with such necessity. I therefore specifically employ a distributor bar or rail which consists of detachable sections, each section corresponding to one of the magazines in use, so that when another magazine is substituted for one of them, the section of the distributor bar corresponding thereto may be removed and replaced by an appropriate section without disturbing or affecting the section which co-acts with the magazine left in position. It will be understood of course that it may not be necessary to remove the distributor bar section each time the corresponding magazine is removed, as in certain circumstances the substituted magazine may not require it. The point is that in some cases the distributor bar section is not adapted to distribute the matrices to a substituted magazine and it then becomes necessary to replace it by another of different form.

The accompanying drawings illustrate a linotype machine having my invention applied thereto, and except as hereinafter specifically set forth, it may be of the general type illustrated in Letters Patent No. 436,532, to O. Mergenthaler, granted September 16, 1890, or the Muehleisen patent previously mentioned.

While I illustrate a preferred embodiment of my invention, it will be obvious that many changes and alterations may be made therein without departing from its spirit. Thus for instance, it may be similarly used in connection with type setting machines, or in fact any kind of typographical machine; and I therefore desire it to be distinctly understood that I do not limit myself to any specific form or embodiment except in so far as such limitations are specified in the claims.

Referring to the drawings: Figure 1 is a perspective view of a linotype machine embodying my invention; Fig. 2 is a detached

view, partly broken away, of the keyboard mechanism for the supplemental magazine; and Fig. 3 is a detail view showing the sectional construction of the distributor rail or bar.

Referring to the drawings, and generally speaking, the matrices are stored in the magazines A and A¹ and are released therefrom by the proper manipulation of the respective keyboards B and B¹, whereby they are delivered upon the common assembling belt C, and by it in turn to the assembler D, from which the composed line is transferred to the casting mechanism E. After the linotype is cast in the usual manner, the matrices are conveyed to the top of the machine and there transferred to the distributor bar or rail F and F¹, from which they drop into the magazines A and A¹.

In present instance I have shown one additional or supplemental magazine A¹, in line with the magazine A, to contain the extra matrices which may be desired from time to time in composition, and from which they pass to their common assembling belt C. The matrices are controlled and released from the magazine A¹ by ordinary escapement devices, which are not herein specifically described and illustrated for the reason that they constitute no part of my present invention. These escapements are actuated from the secondary or supplemental keyboard B¹ (see particularly Fig. 2), which is provided with appropriate finger pieces, such as the push buttons B², B², corresponding to the several matrices contained in the magazine. The operating connections from the push buttons B², B², may be of any desired construction, and are herein conventionally illustrated as comprising pivoted levers B³, B³, actuated by the push buttons B², B², and in turn operating the escapement reeds or bails B⁴, B⁴, which act upon the escapement devices, not shown.

The magazine A¹ may be removed from its position and replaced by another selected magazine, and in order to facilitate this interchangeability, I provide it with suitable means for shifting it, such for instance as the cam pieces A², A², which may be constructed and may operate in substantially the same manner as the similar cam pieces illustrated in the patent to Homans, No. 830,436, granted September 4, 1906. Such means, however, constitute no part of the present invention and are illustrated and referred to herein simply by way of example, as any well known or obvious means may be employed for the purpose of permitting the removal and replacement of the magazine.

As previously stated, in the Muehleisen type of machine, the distributor bar or rail is extended entirely across the upper ends of both magazines so as to carry and deliver the matrices to their appropriate

channels in either of them, and in the present instance the general principle remains the same, the matrices being passed along the rail portion F, from which they drop into the magazine A, and then along the continued portion F¹ from which they drop into the magazine A¹. In order, however, to adapt the machine to a variety of interchangeable magazines, I construct the rail in two separable sections F and F¹ (see particularly Fig. 3) which may be detachably secured together in any desired manner, as for instance by a bolt F². In Fig. 3 the rail section F is shown as formed with sustaining lips or teeth for the matrices of considerably greater extent than the similar sustaining lips or teeth on the section F², this difference being indicated by the dotted lines 1, 1, 1, in connection with the section F, and the dotted lines 2, 2, 2, in connection with the section F¹. Assuming by way of example, that for the magazine A¹ another magazine should be substituted containing a different number of tubes or receptacles, or to carry matrices having a different thickness from those carried by the previous magazine A¹, it will be necessary that the distributor bar above the new magazine be formed with different sustaining lips or teeth and of correspondingly different extent. My improved construction enables me to comply with this requirement without removing the entire distributor rail from the machine and substituting another therefor, as all that is necessary is to replace the section F¹ by one corresponding in formation and permutation to the new matrices which are brought into play by the new magazine. In other words, this sectional construction of the distributor bar, and the detachable connection, allow me to adapt the distributing mechanism to any change of matrix or face with the minimum of expense and trouble.

As previously stated, numerous modifications such as will suggest themselves to those skilled in the art may be made in my construction and its adaptation without departing from the spirit of my invention.

Having thus described my invention, its construction and mode of operation, what I claim and desire to secure by Letters Patents of the United States, is as follows:

1. Distributing mechanism for typographical machines comprising sections formed with character-distributing combinations, one of said sections being replaceable at will by a section of dissimilar character to effect an alteration in or rearrangement of the distributing combinations of the distributing mechanism.

2. A toothed distributor bar for linotype machines comprising a section replaceable at will by a section of dissimilar character to effect an alteration in or re-arrangement

of the tooth combinations of the distributor bar.

3. In a typographical machine, the combination of a plurality of magazines, one removable independently of another, and distributing mechanism comprising a plurality of sections, one for each magazine, one of said sections being replaceable at will by a section of dissimilar character; whereby the distributing mechanism may be altered to correspond to different magazines.

4. In a typographical machine, the combination of a plurality of magazines, one removable at will from the machine, and dis-

tributing mechanism therefor comprising a 15 toothed distributor bar formed in sections, one for each magazine, the section corresponding to the removable magazine being replaceable at will by a section corresponding to a substituted magazine.

In testimony whereof I hereunto set my hand this 4th day of May, 1911, in the presence of two attesting witnesses.

DAVID S. KENNEDY.
